E. S. HELWITZ.

SHOE HEEL.

APPLICATION FILED MAR. 20, 1917.

1,263,555.

Patented Apr. 23, 1918.

Ellis S. Helwitz Inventor
By his Attorney

Isaac Stevens

UNITED STATES PATENT OFFICE.

ELLIS S. HELWITZ, OF BROOKLYN, NEW YORK.

SHOE-HEEL.

1,263,555.

Specification of Letters Patent.

Patented Apr. 23, 1918.

Application filed March 20, 1917. Serial No. 155,983.

To all whom it may concern:

Be it known that I, ELLIS S. HELWITZ, a subject of King George V of Great Britain and Ireland, and a resident of the borough of Brooklyn, city and State of New York, have invented certain new and useful Improvements in Shoe-Heels, of which the following is a description in such full, clear, and exact terms as will enable any person skilled in the art to which it pertains to make and use the same.

My invention relates to a rubber heel adapted to be detachably placed on the heels of leather shoes to soften the tread of the wearer. It is especially adapted to what are known as French heels on women's shoes.

The object of the invention is to provide a practicable rubber heel pad which may be easily attached to and detached from the shoe without the employment of any extraneous fastening devices such as screws, or the like and which will embody a means for causing it to adhere to the pavement and prevent it from slipping under the pressure of the wearer.

To this end my invention comprises certain novel features of construction and relative arrangement of parts which will be fully set forth hereinafter and particularly pointed out in the claims.

Reference is had to the accompanying drawing which illustrates the preferred embodiment of my invention.

In this drawing—

Figure 1 is a section view of the heel pad in position, and

Fig. 2 is a bottom plan view of the same.

The heel pad is formed of a proper composition of soft rubber with a base or pad proper *a* adapted to lie under the top lift of the heel and with an elastic uprising wall *b* which tapers upwardly and inwardly and is adapted to embrace the flaring lower part of the French heel so that the elastic wall holds the rubber pad or detachable heel in place.

It should be noted that this wall *b* holds the pad securely and yet removably in position and allows the device to be applied to the heels of shoes without the use of any other fastening devices and without necessitating the employment of skilled labor such as the labor of a shoemaker in attaching rubber heels by screws, nails and like fastenings. It will further be noted that by attaching the heel in this way a large meas-

ure of freedom of movement is provided for the pad which increases the flexibility of the device and the cushioning effect thereof.

The bottom of the pad *a* is formed with a number of cavities *c* which open on the under side of the pad *a* and directly above these cavities *c* are protuberances or knobs *d*. Each cavity *c* has a corresponding knob or protuberance *d* above it and these protuberances are engaged by the under side of the heel in the manner shown in Fig. 1.

The result of this construction is that when the weight of the wearer is applied to the pad *a* it is first imparted to the projections *d* which flex the soft rubber pad, *a*, and open the cavities *c* causing these cavities to exert a suction on the sidewalk or pavement and prevent the heel from slipping under the wearer.

This operation is largely dependent upon the absence of rigid fastening devices by which the pad *a* is attached to the heel and by reason of the flexible wall *b* the pad is attached to the heel so that the projections *d* and cavities *c* are permitted to function fully and are not cramped and restrained by any rigid fastenings between the pad and the heel which would interfere with the proper action of the parts. In other words, as noted in Fig. 1, the main portion of the

bottom pad proper is held normally slightly spaced from the bottom of the heel by the projections *d*, said main portion of the pad being free to move toward and from the bottom of the heel as a result of the treading upon the device. The attachment means *b* for the pad being operative around the sides of the heel only facilitates or makes possible this free movement of the pad portion of the device toward or from the bottom of the heel and it is by virtue of this freedom of movement that the pressure applied upon the projections *d* will cause the cups *c* to function in the manner already set forth. I wish, however, to call attention in this connection to the ribs *e* indicated as parallel circles projecting downwardly from the bottom of the pad and surrounding the five cups *c*. These circular ribs increase the suction effect of the cups by providing a sure air-tight fit with the walk or pavement. They furthermore by giving a slight elevation to the cupped portion of the pad increase the gripping or traction effect of the cups. In conclusion, therefore, it is to be noted that the buoyancy or resiliency and

the suction effect of my improved heel as herein set forth are both materially enhanced, first and principally by the fact that the means for securing the pad to the shoe heel is all disposed above the plane of the heel and also by the provision of the slight normal space between the main portion of the pad and the bottom of the heel. These facts are substantiated not only by the general structure of the device but are strengthened by the circular rib or ribs *e* surrounding the cups.

What I claim is:—

1. A soft rubber pad for shoe heels comprising a base part or pad proper adapted to lie under and with the main portion thereof normally spaced slightly below the heel and an upstanding inwardly contracted wall extending from the edges of the pad, the wall being adapted to embrace the lower portion of the heel and contract against the same and constituting the only means to hold the base or heel pad proper yieldingly in place, and said base having a series of suction cavities on its under surface and a series of corresponding protuberances on its upper surface, the protuberances respectively above the cavities and engaged by the

lower end of the heel for the purpose specified.

2. The herein described pad for shoe heels composed entirely of solid flexible rubber and comprising a base and an integral surrounding gripping flange, said base being designed to be carried below the shoe heel while the flange is adapted to grip around the walls of the heel and hold the pad firmly in place, said base being provided on its bottom surface with a concavity forming a suction cup and having a downwardly projecting rib surrounding the cup, and the upper surface of the pad base being formed with means coöperating with the shoe heel and acting to hold the main portion of the base spaced normally from the bottom of the heel except when pressure is applied to said means to cause the aforesaid cup and surrounding rib to function.

In testimony whereof I have hereunto signed my name in the presence of two witnesses.

ELLIS S. HELWITZ.
